US0D1102368S

(12) **United States Design Patent** (10) **Patent No.:** **US D1,102,368 S**
Wang (45) **Date of Patent:** **** Nov. 18, 2025**

(54) **RECHARGEABLE BATTERY**

(71) Applicant: **SHENZHEN ORIENTAL WILLING NEW ENERGY CO., LTD**, Shenzhen (CN)

(72) Inventor: **Kunli Wang**, Shenzhen (CN)

(73) Assignee: **SHENZHEN ORIENTAL WILLING NEW ENERGY CO., LTD**, Shenzhen (CN)

(**) Term: **15 Years**

(21) Appl. No.: **29/952,597**

(22) Filed: **Jul. 17, 2024**

(30) **Foreign Application Priority Data**

Jul. 5, 2024 (CN) 202430420855.4

(51) **LOC (15) Cl.** **13-02**

(52) **U.S. Cl.**

USPC **D13/103**

(58) **Field of Classification Search**

USPC D13/103–106, 110, 118, 119, 184, 199

(57) **CLAIM**

The ornamental design for a rechargeable battery, as shown and described.

DESCRIPTION

FIG. 1 is a front perspective view of a rechargeable battery, showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a perspective view showing the rechargeable battery in a use state.

The broken lines in the drawings illustrate the portions of the rechargeable battery, which form no part of the claimed design.

1 Claim, 8 Drawing Sheets
